(57) **CLAIM**

The ornamental design for the measuring tape device, as shown and described.

DESCRIPTION

FIG. 1 is a perspective view of a measuring tape device in accordance with an embodiment of the present invention; FIG. 2 is a right side view of the measuring tape device of FIG. 1;

FIG. 3 is a left side view of the measuring tape device of FIG. 1;

FIG. 4 is a rear view of the measuring tape device of FIG. 1;

FIG. 5 is a front view of the measuring tape device of FIG. 1;

FIG. 6 is a top view of the measuring tape device of FIG. 1; and,

FIG. 7 is a bottom view of the measuring tape device of FIG. 1.

The broken lines of the measuring tape device in FIGS. 1-7 are illustrative of portions of the measuring tape device that form no part of the claimed design.

1 Claim, 7 Drawing Sheets
